SHUTTLE

William E. Jennings, West Warwick, R. I., assignor to U. S. Bobbin & Shuttle Company, Lawrence, Mass., a corporation of Rhode Island

Application May 19, 1937, Serial No. 143,436

11 Claims. (Cl. 139—223)

This invention relates to weaving shuttles of the self-threading type and more particularly to an arrangement of the component parts of such a shuttle to provide an effective thread-guiding arrangement including a yarn trap associated with the yarn delivery eye, thus to prevent unthreading of the shuttle.

In accordance with this invention, the thread guide block may be arranged to prevent the accidental upward movement of the thread out of the delivery eye, while affording an arrangement of parts permitting the normal movement of the thread over smooth wear-resistant surfaces without liability of the thread cutting into the metal of the guide block as the shuttle moves back and forth. Preferably a part of the shuttle itself may be arranged to cooperate with a portion of the guide block in affording a trap to prevent the upward movement of the yarn out of the delivery eye, while allowing the ready downward movement of the yarn during the self-threading action of the shuttle. To permit these desirable results, the metal of the guide block is preferably provided with a portion above the delivery eye, which in effect affords an outer lip with a reentrant part disposed inwardly from this lip, while a horn-like projection of the wood or the like of the body of the shuttle extends into this reentrant portion of the guide block. Thus parts are provided to define a tortuous channel through which the yarn may move when first passing to the delivery eye, the tortuous contour of this channel being effective in preventing the upward movement of the yarn. The metal of the block below this portion may be cut away to afford a relatively smooth walled open passage provided with two guide pins which may be formed of wear-resistant material. A third guide pin may be arranged in the body portion of the shuttle to cooperate with one of the guide pins carried by the thread-guiding block in defining the eye portion of the shuttle, the horn-like projection of the shuttle body projecting over and rearwardly from the third guide pin.

45 In the accompanying drawing:
Fig. 1 is a side elevation of the end portion of an improved shuttle constructed in accordance with this invention;

50 Fig. 2 is a plan view of the portion of the shuttle shown in Fig. 1;

Fig. 3 is a bottom view of the guide block employed in the shuttle shown in Figs. 1 and 2;

Fig. 4 is a front elevation of the guide block;

Fig. 5 is an enlarged section on line 5—5 of Fig. 1; and

Fig. 6 is a plan view of the end of the body portion of the shuttle with the guide block removed.

In the accompanying drawing, which illustrates the principles of the present invention, the numeral 1 designates the body of a weaving shuttle of the type commonly employed in automatic looms, this shuttle being provided at its front end with a conventional metal tip 2. The shuttle body, which may conveniently be formed, for example, of wood, is provided with a chamber 3, Fig. 2, for the reception of a bobbin 4. This chamber has a forward extension 5, Fig. 6, for the reception of the thread guide block 6, which may be held in place by any suitable means. This block may conveniently be formed of metal or of any other suitable material. The side of the shuttle body 1 is provided with the usual longitudinally extending shallow thread groove 8 having a forward extension 9 at one side of the thread delivery eye and an extension 9a at the opposite side thereof. The chamber 5 is provided with a lateral extension 5a between these portions 9 and 9a of the exterior thread groove. The block 6 may have a flat bottom surface 10 which seats upon the bottom of chamber 5 of the shuttle body 1 and may have spaced side walls 11 and 12 between which is the longitudinally extending portion 13 of the yarn guide passage. Near the entrance end of this passage suitable tension plates 17 may be provided yieldably to engage the yarn. These plates may conveniently be arranged in any suitable manner such as that disclosed in the copending United States application of Carl P. Park, Serial No. 101,630.

The block 6 may be provided with a substantially horizontal guide pin 29, Figs. 3 and 4, arranged in the longitudinal portion 13 of the yarn passage and preferably at a point just forward of the tension plates 11, in the manner disclosed in the above-identified Park application, this pin 40 being at such an elevation that the projected axis of the bobbin 4 lies substantially tangential to its upper surface. The block 6 is also preferably provided with an inner substantially vertically disposed guide pin 30 at the junction of the longitudinal portion 13 of the thread passage and a transverse continuation 16 of said passage which leads to the thread delivery eye. The pin 30 may conveniently be formed of porcelain or other wear-resistant material. The block 6 has a lateral extension 6a which is disposed in the upper part of the extension 5a of the chamber 5. This extension 6a of the block is provided with convexly curved lateral and upper outer faces which merge into 55

- each other and which substantially conform in curvature to the curvature of the adjoining surface portions of the body portion of the shuttle, Figs. 1 and 4. The extension 6^a has a downwardly directed leg portion whose lower substantially horizontal surface overhangs the delivery eye. The extension 6^a also comprises an inwardly and forwardly directed horn-like projection 6^b which is separated by an upwardly-flared recess 27 from a relatively small forwardly directed pointed projection 28 from the rear part of the wall 12 of the guide block which overlies the major portion of the width of the longitudinal guide passage 13.
- 15 The extremity of the horn-like projection 6^b is provided with a downwardly curved tip 6^c, Fig. 1. The forward surface of the leg portion of the extension 6^a is provided with a cavity or reentrant part 6^d, Fig. 4, which cooperates with the outer lateral and upper surfaces of this portion of the block in defining a relatively thin, curved lip or flange 6^e forming the upper wall of the cavity and which extends upwardly along the side and top of the extension 6^a and which merges into the relatively thicker edge of the forward part of the horn-like projection 6^b and its downturned tip 6^c. Below the cavity 6^d the metal of the block may be provided with a smoothly finished surface which gradually curves into the lower surface 6^f of the leg portion of extension 6^a.
- 20 The block 6 is also provided with a lower lateral extension 40 which is connected to the upper extension 6^a by a metal wall 31 which engages the wall of the lateral extension 5^a of the chamber 5, Fig. 5. A second guide pin 34 is disposed adjoining the outer end of the metal wall 31 and slightly inwardly from the overhanging lower edge of the lip 6^e and of the outer extremity of the lower lateral extension 40 of the block. The wall 11 of the block has a forward extension 35 with a concavely curved surface in closely spaced relation to the convexly curved surface of the adjoining part of the tip 6^c of the extension 6^b of the block, Figs. 3 and 4.
- 25 The shuttle body preferably is provided with a rearwardly directed horn-like projection or guard 36 which has a tip portion 36^b extending into the cavity 6^d of the guide block in close juxtaposition to and inwardly of the lower part of the lip 6^e, the tip 36^b being concealed from view behind the lip. This lip and the adjoining part of the metal block thus provide a groove which is V-shaped in horizontal section, as shown in Fig. 5, and the tip 36^b of the projection 36 extends into this groove 30 in closely spaced relation to the walls thereof. Preferably the upper and lateral outer surface of the horn 36 may be convexly curved while its lower surface may be nearly planar.
- 35 A third wear-resistant guide pin 37 is disposed between the inner portion of the horn 36 and the lower wall of the chamber extension 5^a, as shown in Figs. 1 and 5. Accordingly the guide pins 34 and 37 define the sides of the yarn or thread delivery eye.
- 40 As shown particularly in Fig. 5, the walls of grooves 9 and 9^a curve inwardly and these grooves are deeper adjoining the opening in which the pins 34 and 37 are located. The shuttle is also provided with a longitudinal groove 14 on the upper surface of its end portion to receive the yarn during the first pick.
- 45 When the thread or yarn is initially received by the shuttle it engages the upper parts of tension plates 17 in the guide passage 13, passing through the narrow channel between the exten-
- 50 sion 28 of wall 12 of the block and the wall 11 thereof and passing through the narrow space between the tip 6^c of the extension 6^b and the reentrant portion of the extension 35 of the block. From here the yarn may extend along the groove 5 14, as shown in Fig. 2, which illustrates the position of the yarn during the first pick. When the shuttle then moves in the opposite direction, the yarn finds its way downwardly beneath the horn 6^b and through the narrow tortuous channel between the lip 6^e and the rearwardly directed horn-like projection 36 of the shuttle body, passing the tip 36^b of this horn, thus finding its way through the V-shaped channel shown in Fig. 5 and then being received by the delivery eye. 15 Thereupon the thread becomes lodged in its normal channel so that it passes between the cooperating faces of the tension plates 17 over the horizontal guide member 29 and about the guide pin 30, alternately engaging the guide pins 34 and 20 37 at opposite sides of the delivery eye as the shuttle moves back and forth along its path, these two positions of the yarn being indicated by dot and dash lines in Fig. 5.
- 55 During the movement of the yarn from the pin 30 along either of these paths, it is out of engagement with any depending metal projection or the like so that liability of cutting grooves in the metal of the block 6 is avoided. As the yarn moves from its position in engagement with the pin 34 to that in engagement with the pin 37 or vice versa, it is located below the lower horizontal surface of the leg portion of the extension 6^a and of the tip 36^b of the horn, these parts being in spaced overlapping relation so that the 35 yarn can not find its way upwardly out of the delivery eye. In this connection it may be noted that the lower substantially horizontal surface of the downwardly directed leg portion of the extension 6^a of the block 6 together with the lower end of the lip 6^e are disposed slightly below the lower substantially horizontal surface of the horn-like projection 36 of the shuttle body, as shown in Fig. 1. Thus, as the thread moves from one side of the delivery eye to the other, it is 45 protected from catching on the somewhat pointed tip of the horn-like projection 36, while during its movement in the opposite direction it may be guided by the curved lower corner of the lip 6^e past this portion of the block.
- 60 It is evident that when the yarn is in the intermediate position indicated by dot and dash lines in Fig. 5, it is impossible for it to move up through the tortuous channel between the parts 6^b and 36 and even that when the yarn is pulled upwardly by hand with a run disposed under tension in a vertical position, as illustrated in Fig. 1, it is impossible for the yarn to move upwardly through the tortuous channel; thus unthreading of the shuttle is effectively prevented. 65 Accordingly an arrangement is provided whereby the self-threading action of the shuttle is readily permitted and whereby the yarn in its various operative positions is kept from normal engagement with the metal of the block adjoining the delivery eye, while unthreading movement is effectively prevented.
- 65 I claim:
1. A self-threading weaving shuttle comprising a bobbin-receiving chamber, a yarn passage at 70 the end of the chamber, the passage having a lateral extension providing a delivery eye, the shuttle having closely spaced parts providing an irregular channel communicating with the passage and its extension, through which channel 75

the thread may pass to be received at the delivery eye, one of the parts providing a generally V-shaped cavity above the delivery eye, a cooperating part providing a portion projecting into said cavity in closely spaced relation to the walls thereof, so that a channel of generally V-shaped form in horizontal section is afforded above the delivery eye.

5 2. A self-threading shuttle comprising a body portion, a thread guiding block disposed in a recess of the body portion, said block providing a longitudinal yarn passage provided with a transverse portion leading to the delivery eye, the block comprising a lateral extension having a 10 downwardly directed leg whose lower surface overhangs the delivery eye, the outer lateral and upper surfaces of said extension being so shaped as to form a thin lip leading upwardly and forwardly from the delivery eye, the material of the 15 body portion of the shuttle having a rearwardly directed horn-like projection whose tip is concealed behind said lip of the block and which is spaced from the lip to provide a threading passage leading to the delivery eye.

20 25 3. A self-threading shuttle comprising a body portion, a thread guiding block disposed in a recess of the body portion, said block providing a longitudinal yarn passage provided with a transverse portion leading to the delivery eye, the block comprising a lateral extension having a lower surface which overhangs the delivery eye, the material of said extension having therein a 25 forwardly open cavity whose outer wall extends upwardly and forwardly from the delivery eye, 30 the material of the body portion of the shuttle comprising a rearwardly directed horn-like projection whose tip is disposed within the cavity in the block and spaced inwardly from the outer wall of the cavity thereby to provide a threading 35 40 passage leading to the delivery eye.

4. A self-threading shuttle comprising a body portion, a thread guiding block disposed in a recess of the body portion, said block providing a longitudinal yarn passage provided with a transverse portion leading to the delivery eye, the block comprising a lateral extension having a lower surface which overhangs the delivery eye, the material of said extension having therein a 45 forwardly open cavity whose outer wall extends upwardly and forwardly from the delivery eye, the material of the body portion of the shuttle comprising a rearwardly directed horn-like projection whose tip is disposed in closely spaced 50 relation to the outer wall of said cavity to cooperate therewith in defining a horizontally tortuous channel through which the thread may move into the delivery eye, a wear-resistant 55 guide pin on the block about which the thread turns in moving from the longitudinal passage to the eye, a pair of guide pins supported respectively by the block and body portion and defining respectively the opposite sides of the delivery eye, the projection of the block and the cooperating extension of the body portion affording substantially planar surfaces above said eye, the block and body portion providing an open uninterrupted 60 passage between the first-named pin and said eye.

65 5. A self-threading shuttle comprising a body portion, a thread guiding block disposed in a recess of the body portion, said block providing a longitudinal yarn passage and having a lateral extension extending to a delivery eye, said extension comprising a horn-like projection having a convexly curved outer and upper surface

and being provided with a forwardly open cavity above the delivery eye, the extension including an outer lip which forms the outer wall of said cavity, the material of the body portion providing a cooperating horn-like extension with a tip disposed in spaced overlapped relation to said lip to cooperate with the walls of said cavity in defining a tortuous channel through which the thread may move into the delivery eye, the lower part of said projection extending below the adjoining part of the horn-like extension and the lower end of said lip providing a gradually curved lower corner below the tip of said extension.

7. A self-threading weaving shuttle comprising a body portion having a bobbin-receiving chamber, a thread-guiding block disposed in a recess of the body portion, said block providing a longitudinal yarn passage and having a lateral extension extending to a delivery eye, a guide pin supported by the block for defining one side of the eye, a guide pin supported by said body portion and defining the opposite side of said eye, a thread guide pin about which thread may normally turn in passing from the longitudinal passage to said eye, said extension of the block affording a horn-like projection with convexly curved outer and upper surfaces and with a downturned tip spaced inwardly from and above said eye, a lip extending from said tip along the edge of the extension and terminating in a curved corner above the delivery eye, the material of the body portion providing a cooperating horn-like extension with a tip disposed over the eye, said tip being in spaced overlapping relation to said extension of the body portion, said last-named extension and the extension of the block providing lower surfaces to define the upper wall of the delivery eye, said corner being disposed slightly below the adjoining lower surface of the projection of the body portion, thereby to engage a rearwardly moving but upwardly stressed thread with a cam-like action.

7. Automatically threading loom shuttle provided with a threading block having a downwardly extending leg portion, the lower end portion of which forms part of the side delivery eye, and a guard formed by the wood of the shuttle and extending back of and in overlapping relation with the leg portion of the threading block with a space between to permit the filling thread to pass between the two and thereafter be prevented from escaping from the side delivery eye during weaving.

8. An automatically threading loom shuttle provided with a metal threading block having a downwardly extending leg provided with a straight terminal end to form part of the threading eye and the wood of the shuttle contrived to form another portion of the side delivery eye with the end of the shuttle wood extending rearwardly back of the lower edge of the leg with a space between to permit complete threading of the shuttle and thereafter acting as a guard to prevent unthreading of the shuttle during weaving.

9. An automatically threading loom shuttle having a threading block provided with a downwardly extending leg, the lower end of which forms a part of the side delivery eye and the wood of the shuttle being cut to provide the complementary portion of the side delivery eye of slightly greater height than the end of the leg with the end portion of the wood of the shuttle extending back of the lower edge of the leg with a space between for the entrance of the filling thread

during threading and forming a guard to prevent the filling thread from escaping from the side delivery eye during weaving.

10. A self-threading shuttle comprising a body portion, a thread guiding block disposed in a recess of the body portion, said block providing a longitudinal yarn passage and having a lateral extension extending to a delivery eye, said extension affording a horn-like projection with a convexly curved outer and upper surface, a cavity above the delivery eye, the extension providing an outer lip extending along said cavity, the material of the body portion providing a cooperating horn-like extension with a tip disposed in spaced overlapped relation to said lip to cooperate with the walls of said cavity in defining a tortuous channel through which the thread may move into the delivery eye, the lower part of said projection extending below the adjoining part of 15 the horn-like extension and the lower end of said lip providing a gradually curved lower corner below the tip of said extension.

11. In a loom shuttle, a shuttle body recessed to provide a longitudinal thread passage and a transverse thread passage, a separate threader block mounted in said recess, said block having a thread-retaining portion overlying said longitudinal thread passage and having a transversely disposed wing extending downwardly to said transverse thread passage at the side of the shuttle and having its lower edge forming the upper side of said thread passage, and a thread-retaining element positioned in said shuttle in advance of said wing and cooperating therewith to provide a narrow transverse threading slot, said retaining element having a rearwardly elongated portion having a warped thread-guiding surface 15 and extending back of the lower portion of said wing and longitudinally overlapping the thread-guiding forward edge thereof, and said element and wing cooperating to prevent unthreading of the shuttle.
